Robt. D. Pearson,
ATTORNEY.

UNITED STATES PATENT OFFICE.

CHARLES L. W. HAYNES, OF OCEAN PARK, CALIFORNIA.

COIN-CONTROLLED LOCK.

Application filed July 25, 1923. Serial No. 653,682.

To all whom it may concern:

Be it known that I, CHARLES L. W. HAYNES, a citizen of the United States, residing at Ocean Park, in the county of Los Angeles and State of California, have invented certain new and useful Improvements in Coin-Controlled Locks, of which the following is a specification.

My invention relates to a coin-controlled lock, especially suitable for use in connection with a swinging door.

The objects of this invention are first, to construct a coin actuated device of this kind which may be positively operated on the deposit of a coin of a predetermined denomination or value; second, to construct a coin or key controlled rotary barrel and sleeve mechanism for coin locks; third, to use a type of coin control for locks that possess advantages in its simplicity in construction and operation.

Reference is to be had to the accompanying drawings forming a part of this specification, in which similar characters of reference indicate corresponding parts in all the figures.

Figure 1 represents a front elevation of the coin controlled lock, in part section on line 1—1 of Figure 2.

Figure 2 represents a side elevation of the said lock, in part section on line 2—2 of Figure 1.

Figure 3 represents a plan view of Figure 1.

Figure 4 represents a sectional view on line 4—4 of Figure 2, with parts removed.

Figure 5 represents a plan view of Figure 4, with parts removed.

Figure 6 represents a sectional view on line 6—6 of Figure 2.

Figure 7 represents a plan view of the shaft with a portion of the key in position.

Figure 8 represents a sectional view on line 8—8 of Figure 7, with the key in position.

Figure 9 represents an end view of Figure 8, with the key removed.

The lock comprises a housing 1 with a plate 2 being locked in the under side thereof, and a slot 8 passes through the upper side thereof, a bolt 9 passes operatively through the said housing 1 and extends operatively into a strike 3, the said housing 1

and strike 3 being secured to a door 6 and a wall 7 respectively. The bolt 9 is positioned operatively between the guides 10, the said guides 10 being integral with the rear shell of the housing 1, and a spring 11 is positioned in tension against the rear end portion of the said bolt 9 and is secured around a pin 13, and the said pin 13 is secured in the lower-inner portion of the rear shell of the housing 1. A pin 14 is secured on the central portion of the bolt 9, and a pin 15 is in turn secured in the rear shell of the housing 1, adjacent to the arm 20 when the said bolt 9 is in an extended position in the said strike 3. The shaft 19 passes operatively through the door 6 and the rear shell of the said housing 1, and the shell 18 is operatively mounted on the inner portion of the shaft 19 and extends operatively into the outer shell of the housing 1 adjacent to the shoulder 22, the shoulder 22 being integral with the said shell 18 and the handles 4 and 5 are secured to the outer and inner end portions of the said shell 18 and shaft 19 respectively, the said arm 20 is secured to the shaft 19 adjacent to the rear shell of the housing 1 and projects operatively down a distance over the bolt 9 between the pins 14 and 15, and a slot 25 passes through the inner end portion of the shaft 19, and a bar 27 is positioned in the slot 25 adjacent to the hole 26, the said hole 26 passes through the central portion of the shell 18 and handle 4 respectively, to receive a key 28, the slot 23 is formed in the upper half of the shell 18 and extends from the open end portion thereof to the said shoulder 22, and the slot 24 is formed in the lower half of the shell 18 and extends from the open end portion thereof to the said shoulder 22, the finger 21 is integral with the shell 18 and is formed in the outer end of the said slot 24 and extends from one longitudinal side thereof a distance towards the opposite longitudinal side to leave the outer end portion of the said slot 24 partially open, as shown in Figure 5. The said shoulder 22 having stops 29 formed in the upper portion thereof, and the pin 16 is secured in the outer shell of the housing 1 between the said stops 29, and the spring 12 is secured in tension between the shoulder 22 and the inner shell of the housing 1 by the pin 17 and pin 30 respectively.

The coin controlled lock and strike are first connected to a door and a door post respectively, where it is desired to receive payment in coin for permission to enter into a closet or room.

It will be seen in Figure 2 that the coin 31 is first deposited through the slot 8 in the housing 1, and permitted to fall into the slot 25 in the shaft 19, and between the slot 23 in the shell 18, when the lock is in a closed position in the strike 3 as shown in Figures 1 and 3, and one side of the said coin 31 will thus ride on the finger 21 in the slot 24 to form a connection means between the said slots 25 and 24 so as to allow the bolt 9 to be actuated into the housing 1 by turning the handle 4 and shell 18 counter-clockwise to shift the side of the slot 23 against the coin 31 and thus force the shaft 19 and arm 20 in the same counter-clockwise direction to pull the bolt 9 into the housing 1, thus releasing the said bolt 9 from the strike 3 and the door 6 may thus be swung open from the wall 7. It will also be noted that the coin 31 remains in the said slot 25 on the finger 21 when the said handle 4 is actuated to open the door 6, and thus after the occupant of the said closet or room wishes to make an exit through the said door 6 after the same was closed behind him, the handle 5 is turned clockwise from the inside of the door 6, thus the shaft 19 actuates the arm 20 and bolt 9 in a like manner as hereinbefore described independently of the said coin 31, and as the said shaft 19 is turned by the handle 5 the coin 31 will be turned loose from the finger 21 and fall through the slot 24 into the lower-inner portion of the said housing 1. When it is desired to operate the lock from the outside of the door 6 without a coin 31 a key 28 may be employed by being inserted through the hole

26 in the handle 4 and shell 18, and around the bar 27 in the slot 25.

Having thus described my invention what I claim is:

In a coin-controlled lock of the class described, the combination of a housing, a coin chute extending through the top of the housing, a shaft journaled in said housing and extending through the rear wall thereof, a shell journaled in said housing on said shaft and extending through the front wall of the housing, said shaft having a slot extending diametrically therethrough, said shell having a pair of slots located diametrically opposite each other and said slots being wider than said shaft slot and adapted to register therewith, a finger formed integral with said shell at the outer end of its lower slot projecting part way across said slot for arresting a coin deposited through said chute and into said shell slots and said shaft slot, a stop in the housing, a shoulder on said shell, a spring for normally holding the shell in position with said shoulder against said stop with the slots in the shell in vertical alignment with said chute, a bolt slidably mounted in said housing for engaging a catch, a spring for normally holding said bolt in engagement with said catch and the slot in the shaft in vertical alignment with the shell slots and said chute, a pin on said bolt, an arm on said shaft for engaging said pin for retracting said bolt when the shell is rotated counterclockwise or when said shaft is rotated clockwise, with a coin deposited in the slots in said shell and said shaft, said coin escaping said finger and dropping into the lower part of said housing upon rotation of said shaft counter-clockwise.

In testimony whereof I affix my signature.

CHARLES L. W. HAYNES.
